[57] CLAIM

The ornamental design for a suction swab, as shown and described.

DESCRIPTION

FIG. 1 is a side elevation view of a suction swab showing my new design, the opposite side being a mirror image thereof;

FIG. 2 is a top plan view thereof;

FIG. 3 is a bottom plan view thereof;

FIG. 4 is an end view thereof taken from the suction end having the four ring connecting portion;

FIG. 5 is an end view thereof taken from the end opposite to that shown in FIG. 4;

FIG. 6 is a side elevational view of a second embodiment of a suction swab showing my new design, the opposite side elevational view being a mirror image thereof;

FIG. 7 is a top plan view thereof;

FIG. 8 is a bottom plan view thereof;

FIG. 9 is an end view thereof taken from the end having the four ring connecting portion; and,

FIG. 10 is an end view therefore taken from the end opposite to that shown in FIG. 9.

+ 1 g.1.+ 1 g.2.+ 1 g.3.+ 1 g.4.+ 1 g.5.

Fig. 6.Fig. 7.Fig. 8.Fig. 9.Fig. 10.
